UNITED STATES PATENT OFFICE.

ROSWELL J. STANLEY, OF MOUNT MORRIS, NEW YORK.

IMPROVEMENT IN HAY-ELEVATING FORKS.

Specification forming part of Letters Patent No. 40,860, dated December 8, 1863.

To all whom it may concern:

Be it known that I, R. J. STANLEY, of Mount Morris, in the county of Livingston and State of New York, have invented a new and useful Improvement in Double Elevating-Forks; and I do hereby declare that the following is a full, clear, and exact description of the same, reference being had to the accompanying drawings, forming part of this specification, in which—

Figure 1 is a plan of my improved fork. Fig. 2 is a vertical section of the same, showing it in two positions.

Similar letters of reference indicate corresponding parts in both figures.

This invention has been more especially designed for forks for the discharging of straw from the bleaches in the manufacture of paper, but may be also applied to agricultural purposes.

It consists in a novel construction of the fork, whereby the opening and closing at the proper time are rendered automatic and the necessity for a separate tackle to open the fork is dispensed with.

To enable others skilled in the art to make and use my invention, I will proceed to describe its construction and operation.

The two sides of the forks are composed of two similar frames or stocks, A A', pivoted together by a pin, a, and each furnished with a suitable number of tines, b b, and the stock A has made in the same piece with or rigidly attached to it an arm, C, and the stock A' has made in the same with or rigidly attached to it a similar arm, C', and the arm C or C' of each fork extends beyond the pivot and over the stock of the other fork. The two arms C C' are connected by two links, D D', which are pivoted to the shackle E, by which the whole apparatus is attached to the rope or chain F, by which the hoisting is effected, the said rope or chain being operated by a crane or other suitable hoisting apparatus.

To the arm C' there is pivoted by a fulerum, c, a small lever, G, to the outer arm of which there is attached a hooked spring-catch, d, which is arranged to hook into a notch, e, in the under side of the stock A, and the inner arm of the said lever is loaded, as shown at f, so as to overbalance the outer arm, and tend to

keep the upper surface of the latter arm above the upper surface of the arm C', as shown in blue outline in Fig. 2, and keep the catch out of the notch e, the weight f then resting against the stock A.

The crane from which the hook is suspended has rigidly attached to it a ring or circular frame, H, through the center of which the rope or chain f passes, and which is so formed that in raising the fork the arms C C' and the outer arm of the catch-lever G will come in contact with it. This ring or frame swings with the hook.

The operation of the fork is as follows: It is lowered into the bleach from which the straw is to be taken, or to the floor or place whence any other material is taken, in the open condition shown in black outline in Fig. 1, in which it is locked by the catch d entering the notch e. When the points of the tines b come to a bearing the other parts still descend till the arms C C' come to a bearing on the stocks A' A, which is sufficient to free the catch d from the notch e and allow the weighted arm of the lever G to drop against the stock A, and so draw out the catch d clear of the stock. As soon as the rope or chain becomes slack, which shows that the hook has descended as far as necessary, the hook is hoisted up, and in this operation it is closed by the action of the arms C C', as shown in Fig. 2, so that it takes up the straw or other material. After the hook has closed, and before the arms C C' come in contact with the frame or ring H, the crane or hoisting apparatus is swung over the receptacle or place into which or where the straw or other material is to be deposited, and the hoisting up is again continued, and the effect of drawing up the arms C C' against the frame or ring is to cause the spreading of the said arms and consequent opening of the hook and discharge of its contents. The outer arm of the catch-lever G also comes into contact with the ring or frame H, and is depressed relatively to the arm C' until flush therewith, and as the hook arrives in its completely-open condition the catch d springs under the stock A and into the notch e, and locks the hook in the open condition shown in Fig. 2, in which condition it remains during its descent.

What I claim as my invention, and desire to secure by Letters Patent, is—

The double fork composed of the two stocks A A', with their attached tines, the two arms C C', two links, D D', and the catch-lever G, and spring-catch d, or their equivalent, attached to one of the arms C C', the whole com-

bined and operating substantially as and for the purpose herein specified.

ROSWELL J. STANLEY.
